ATTORNEYS

UNITED STATES PATENT OFFICE.

JOHN H. KILLION, OF CHICAGO, ILLINOIS.

METAL LATH.

Application filed September 17, 1926. Serial No. 136,149

My invention relates to improvements in metal lath, and it consists in the combinations, constructions, and arrangements herein described and claimed.

5 An object of my invention is to provide a metal lath which is so constructed that there is a minimum waste of plaster.

A further object of the invention is to provide a metal lath which is so constructed that even though the sheet is lighter in weight than the ordinary metal lath, it is stronger and will resist bending and pressure to a greater extent than the ordinary metal lath.

15 A further object is to provide a metal lath which can be readily manufactured by means of rolls instead of by reciprocating dies, thus further decreasing the cost of manufacture.

20 A further object is to provide a metal lath so constructed that the teeth or dies which cut the lath leave it in such a condition that the teeth may be readily withdrawn, thus permitting devices like rolls to be used and speeding up production.

25 Other objects and advantages will appear in the following specification, and the novel features of the invention will be particularly pointed out in the appended claims.

30 My invention is illustrated in the accompanying drawings, forming part of this application, in which

Figure 1 is a face view of a section of lath constructed according to my invention,

35 Figure 2 is a section along the line 2—2 of Figure 1,

Figure 3 is a section through one of the ribs,

40 Figure 4 is a section substantially along the line 4—4 of Figure 2 with the plaster in place, and

Figure 5 is a fragmentary portion of a modified form of the device.

45 In carrying out my invention, I provide a thin metal sheet 1 which has stamped thereon a series of parallel ridges 2 on one side to form parallel grooves 3 on the opposite side.

Arranged in parallelism between the grooves or ridges is a series of ribs. Alternate ribs 4 are bowed out on that side of the sheet bearing the grooves 3, while the intermediate ribs 5 are bowed outwardly on that side of the sheet bearing the ridges 2.

50 In addition to being bowed outwardly, each rib is grooved inwardly in a lateral di-

rection, as shown in Figure 3 at 4^a and also 55 in Figure 4.

In forming the ribs in this manner, it will be noted that the metal of each rib must necessarily be drawn in at the side edges so that this leaves a small space or slit 6 between the edges of one rib and the nearest edges of the two ribs on either side thereof which are bowed in the opposite direction. The provision of this slight opening is of great importance in the manufacture of the 65 lath.

From the foregoing description of the various parts of the device, the operation thereof may be readily understood. As will be seen from figure 4, the space between adjacent ribs 4 has immediately behind it a rib 5, so that when the plaster is applied the rib 5 tends to cause the plaster to spread out behind the ribs 4 so as to securely lock the plaster in position, while very little if any plaster will be forced between adjacent ribs 5. The result is that very little, if any, of the plaster will fall off from the rear portion of the lath, but the space between two sheets of oppositely bowed ribs will be 70 completely filled with the plaster, and it will require a minimum of plaster to fill it. 75

80 While I have shown the plaster as applied to that face of the sheet having the outwardly bowed ribs 4, it is obvious that it might be applied from the opposite side with equally good effects, since the same conditions are met, that is to say, that a rib 4 will register with the space between the ribs 5 so as to spread out the mortar in the same manner. 85

85 The bowed shape of the ribs tends to add strength in one direction, while the curvature of the ribs in a direction at right angles tends to add additional strength to each rib. The result is a very strong lath from a relatively thin piece of metal. 90

95 The lath is attached to the studding 7 by means of nails 8 which are placed in the grooves 3 and driven into the studding. It is of course easier to apply the lath by nails which are placed in the grooves, since the grooves tend to center the nails and to permit the quick attachment of the lath. 100

105 In Figure 5 I have shown a modified form of the invention in which the ribs 4^a alternate with ribs 5^a which are disposed at an acute angle with respect to the groove 3^a, so that when the lath is secured in a horizontal

position, the ribs will be inclined to the vertical, or, when the lath is secured in a vertical position, they will be inclined to the horizontal. In both cases the lath is formed of alternate ribs bowed outwardly, each rib having a lateral curvature with respect to the major dimension of the rib.

I claim:

1. A metal lath construction comprising a metal sheet having a plurality of parallel slits, the metal between adjacent slits constituting ribs, alternate ribs being bowed outwardly from the face of one side of the sheet and the remaining ribs being bowed outwardly from the face of the other side of the sheet, and all of said ribs being stamped to provide a trough on the outer convex surface of the rib, and a curved ridge on the

inner surface whereby the original width of the rib is decreased.

2. A metal lath construction comprising a metal sheet having a plurality of rows of parallel slits, the metal between adjacent slits constituting ribs, alternate ribs being bowed outwardly from the face of one side of the sheet and the remaining ribs being bowed outwardly from the face of the other side of the sheet, and all of said ribs being stamped to provide a trough on the outer convex surface of the rib, and a curved ridge on the inner surface whereby the original width of the rib is decreased, that portion of the metal between adjacent parallel rows being stamped to provide a groove on one side of the sheet and a ridge on the opposite side.

JOHN H. KILLION.
